UNITED STATES PATENT OFFICE

2,555,833

ROTARY WHISTLE

Harry R. Vanaman, Millville, N. J.

Application December 6, 1945, Serial No. 633,225

5 Claims. (Cl. 84—330)

1

The invention as described herein, and illustrated in the accompanying drawings, consists of a whistle, an object of which is to provide a whistle so formed that a series of different notes may be emitted therefrom.

Another object of the invention is to provide a rotary whistle.

A further object of this invention is to provide a whistle in the form of a wheel having tubular spokes each of a different depth for producing different notes.

A still further object of the invention is the provision of means whereby in a cheap whistle toy having all of the notes of a major scale upon which melodies may be played thereon when desired.

Another object of the invention is to provide a disk provided with peripheral bores of varying depths and a blower to which the disk is pivoted and rotatable by the blower.

Other features and advantages will become more readily apparent from the following description and the accompanying illustrative drawings in which:

Figure 1 is an elevational view of the whistle, Figure 2 is another elevational view thereof,

Figure 3 is a sectional view on line 3—3 of Figure 2,

Figure 4 is a sectional view on line 4—4 of Figure 1.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claims. And while I have stated the primary field of utility of my invention it remains obvious that it may be employed in any other capacity wherein it may be found applicable.

In the accompanying drawings, and in the following specification, the same reference characters are used to designate the same parts and elements throughout and in which 10, refers to the invention and 11, indicates a bearing member in which is provided an elongated slot 12, within which is rotatably mounted a spoked wheel 14, by means of a pintle 15. The upper end 16, is provided with a substantially horizontal bore 17, having a reduced inner end 18, terminat-

2

ing substantially upon the periphery 19, of the member 14.

The member 14, is in the form of a wheel provided with a hub portion 20, from which project 5 annularly a series of spokes 21, all of which are tubular and the bores 22, 23, 24, of each being of a different depth, whereby various notes will be sounded when the bores selectively align with the reduced end 18 of the bore in the mouthpiece and when the operator blows into the mouthpiece. The wheel has a rim 26 and the outer ends 25 of the bores in the spokes will consecutively align with the reduced end 18 of the bore 17 in the mouthpiece when the wheel is turned.

15 It is obvious that as many tubular spokes may be provided in the wheel as desired. It is also obvious that the bores 22, 23, 24, may be so graduated in depth as to provide a musical scale or octave whereby melodies may be played upon 20 the device simply by using the finger of the user of the device to rotate the wheel backward and forward in order to obtain the desired note.

As will be evident from an inspection of Figure 25 3, a flow of air through the mouthpiece 16 will create a slightly greater pressure on the upper side of any bore of the member 14 aligned with the bore through the mouthpiece, when the device is held as indicated in this figure. The member 14 will, therefore, rotate slowly automatically when the whistle is blown to emit a succession of different tones determined largely by the relative lengths and positioning of the bores in 30 the member 14.

35 From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

40 45 It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of 50 details and parts such as come within the purview of the invention claimed may be resorted to, in actual practice, if desired.

Having now described the invention that which

is claimed to be new and desired to be procured by Letters Patent is:

1. A whistle comprising a bearing member having a slot communicating with a tubular mouthpiece, a wheel freely rotatively mounted on said bearing member and within said slot, said mouth piece having a reduced bore portion adjacent to the wheel, a plurality of bores in said wheel having their axes disposed radially of the wheel, said bores being of different lengths and opening circumferentially of the wheel, said mouthpiece being substantially tangentially disposed with relation to said wheel so that said wheel is automatically rotated when the whistle is blown.

2. A whistle comprising a bearing member having a slot communicating with a tubular mouthpiece, a wheel freely rotatively mounted on said bearing member and within said slot, said mouth piece having a reduced bore portion adjacent to the wheel, a plurality of bores in said wheel having their axes disposed radially of the wheel, said bores being of different lengths and opening circumferentially of the wheel, said slot, wheel and bores being disposed in the same plane, said mouthpiece being substantially tangentially disposed with relation to said wheel so that said wheel is automatically rotated when the whistle is blown.

3. A whistle comprising a bearing member having a slot communicating with a tubular mouthpiece, a wheel freely rotatively mounted on said bearing member and within said slot, said mouth piece having a reduced bore portion adjacent to the wheel, a plurality of bores in said wheel having their axes disposed radially of the wheel, said bores being of different lengths and opening circumferentially of the wheel, said slot, wheel and bores being disposed in the same plane, said mouthpiece being integral with said bearing member and being disposed in the said plane, said mouthpiece being substantially tangentially disposed with relation to said wheel so that said

wheel is automatically rotated when the whistle is blown.

4. A whistle comprising a bearing member having a slot and a tubular mouth piece communicating with the slot, a wheel freely rotatively mounted on said bearing member and within said slot, said wheel having a hub portion and a rim and spokes, said spokes having axial bores opening circumferentially of the rim, and said mouthpiece being disposed tangentially of the rim, said mouth piece having a reduced bore portion adjacent to the wheel and defining an air outlet to cause rotation of the wheel and to create a sound variable according to the speed of rotation of the wheel.

5. A whistle comprising a bearing member having a slot and a tubular mouthpiece communicating with the slot, a wheel freely rotatively mounted on said bearing member and within said slot, said wheel having a hub portion and a rim and spokes, said spokes having axial bores of different lengths opening circumferentially of the rim, and said mouthpiece being disposed tangentially of the rim, said axial bores having closed ends in said hub portion, said mouth piece having a reduced bore portion adjacent to the wheel and defining an air outlet to cause rotation of the wheel and to create a sound variable according to the speed of rotation of the wheel and also variable according to the lengths of the tubes.
